(76) Inventor: **John Thorp**

John Thorp.
Letters Patent.

The schedule referred to in these Letters Patent and making part of the same containing a description in the words of the said John Thorp, himself of his improvement in the spinning of flax & flax twisted yar.

His improvement consists in a cup or case, placed on the top of a deal or steel spindle, around the surface of which the yarn passes being drawn by the bobbin as it turns & receives it. This cup or case serves the purpose of the common flyer, in keeping the yarn at a proper distance from the bobbin, & in guiding & distributing it thereon. The bobbin may be either a weavers bobbin or a common spinning bobbin at the option of the manufacturer, and turns on the spindle receiving its motion from a wheel, which also turns, on the spindle & with which it is connected at its base by two pins or studs extending upward from the wheel & entering the corresponding holes or mortises, in the base of the bobbin. The wheel being banded gives motion to the bobbin, the bobbin motion is similar to the one in common use, excepting that it is made so steady, the spindle, by having the holes through which the spindle passes, of the same size as the spindle. It vibrates like the bobbin rail in common machines, & on it the wheel is set, carrying the motion of the rail moving the bobbin up and down. The spindle & spreading the yarn over the whole length of the bobbin, the lower edge of the cup or case being the guides the rail to which the spindle are confined. In what may be called the spindle rail is a plate of cast iron. In this rail are scores which exactly fit the spindles, & by which with the assistance of an eye or clasp bolt, they are kept perfectly steady, & by these bolts the spindles can easily be adjusted.

and raised or lowered, so that the lower edge of the cup or can, which is the guide of the yarn, may enter the falling of the bobbin.

The cup or can rests $\frac{1}{2}$ in. high upon a shoulder at the top of the spindle, and its cavity is sufficiently large to admit the bobbin. This can be lifted off & put on again with ease, it must be taken off to change the bobbin. To wind or spin the yarn when the bobbin is in the can. The spinning broken ends, or in spinning the yarn the bobbin is lifted by the thumb or finger from the pins, so that it connects it with the whorl, and the whorl is allowed to run while the yarn is put in a proper position to be wound, then the thumb or finger is withdrawn from the bobbin & it falls to its proper place connecting itself again with the whorl. When the spindles are placed close to each other, it may be necessary to surround each cup or can with a cylindrical, semi-cylindrical tube to prevent the yarns from interfering as they pass round their respective cans.
